DISPLAY DEVICE

Filed July 2, 1928

Inventor:
Joseph E. Burgess
By Chever & Cox Atg's

UNITED STATES PATENT OFFICE

JOSEPH EDWIN BURGESS, OF NEW YORK, N. Y., ASSIGNOR TO THE UNITED STATES PRINTING AND LITHOGRAPHING COMPANY, OF BROOKLYN, NEW YORK; A CORPORATION OF OHIO

DISPLAY DEVICE

Application filed July 2, 1928. Serial No. 289,703.

My invention relates to display devices, and more particularly to display devices of the placard type adapted for association with containers and articles of like nature.

5 In general, one of the primary objects of my present invention is to provide a display device or placard of simple and economical construction which may be formed from a single sheet of material such as cardboard, 10 and which is further adapted to be positioned for display purposes upon a container or the like by frictionally engaging the sides thereof.

Another object of my invention is to provide a placard display device in which a very small portion of the lower end of the placard is so formed that upon folding certain of the formed portions, an opening will be presented for receiving the top portion 20 of a container, certain of these folded portions serving to frictionally engage the sides of the container and to thereby secure the placard in a fixed display position upon the container.

25 More specifically, it is an object of my present invention to provide a display device of the placard type in which a relatively small portion of the lower end of the placard is formed and adapted to be folded so as to present an opening for receiving the upper 30 end of a container, certain of these folded portions being designed to engage the rear wall of the container and certain others adapted to interlock therewith and to frictionally engage the sides of the container, thereby to effectively retain the placard in a relatively fixed display position.

35 A still further object of my invention is to provide a placard display device of improved simple construction which is formed at the lower portion thereof with articulations so as to enable the placard to be applied downwardly over the top of a container or to be applied from the rear side of the container and moved forwardly into the desired display position, the folded side portions of the placard frictionally engaging the adjacent side walls of the container sufficiently to 40 secure the placard in a relatively fixed upright position upon the container.

In addition to the above mentioned advantageous characteristics, my invention contemplates the provision of a placard type display device formed from a single sheet of cardboard or similar sheet material, a relatively small lower portion of the placard having members which are adapted to be folded out of the plane of the placard proper, one of the said members having a substantial surface for frictional engagement with the side walls of a 55 container and adapted to hold the other member in a rearwardly folded position for engagement with the rear wall of a container.

60 A still further object of my invention is to provide a placard type display device which adapted for convenient association with containers and the like, said placard having members at the lower portion thereof adapted to be folded out of the plane of the placard and designed not only to frictionally engage the side walls of the container but also to engage the top thereof and to this end I propose to provide a foldable flap which normally bears against the top of the container 65 when the placard occupies an upright position thereon, thereby presenting a display card which can easily be mounted in a relatively fixed position upon a container by frictionally engaging the walls thereof.

70 These and other objects will be more apparent from the following detailed description when considered in connection with the accompanying drawings wherein:

75 Figure 1 is a perspective view of a display device embodying features of my invention, said device being shown in association with a container;

80 Figure 2 is a perspective view of the rear side of the device as shown in Figure 1, the placard proper being shown fragmentarily;

85 Figure 3 is a transverse vertical sectional view of the device taken substantially along the line 3—3 of Figure 2;

90 Figure 4 is a fragmentary view showing the lower portion of the placard with the foldable members thereof positioned within the plane of the placard; and

95 Figure 5 is a fragmentary portion of the lower portion of a placard of alternative or modified construction, this modification resid-

ing in the provision of a depending projection which is adapted to overlie the front wall of the container and to extend below the top of the container.

5 Referring now to the drawings wherein like numerals have been employed to designate similar parts throughout the various figures, it will be seen that my invention contemplates the provision of a placard which I have indicated generally by the numeral 2, the upper portion 3 of which might be considered as a panel or placard proper because it contains the subject matter for display. The lower portion of the placard 10 is formed with an aperture 4, Figure 4, the width of said aperture being substantially equal to the width of a container 6 with which the placard is adapted for association. By forming the placard with the aperture 4, a member or flap 8 is presented which is adapted to be folded out of the plane of the placard proper along articulations 10.

15 It will be noted that I provide the placard with a pair of flaps or side wings 12 which may be folded along articulations 14. These flaps or wings 12 are formed with slots 16 which are coincident with a line forming an extension of the articulation 10 so that when the flap 8 has been folded ninety degrees out 20 of the plane of the placard, the slots 16 of the wings 12 may be swung into interlocking relation with respect to the intermediate portion 18 of the flap 8, as clearly shown in Figures 1 to 3 inclusive. It will thus be 25 apparent that the wings 12 serve to retain the flap 8 in its proper position out of the plane of the placard. In addition to supporting the flap 8 in a fixed proper position, these wings 12 present a surface of substantial size 30 for frictionally engaging the side walls of the container 6 and thereby serve to effectively retain the placard in proper display position with respect to the container. The articulations 14 along which the wings 12 are 35 folded, are positioned in vertical planes which include the opposed inner edges of the flap 8 and hence when said wings are swung through an angle of ninety degrees out of the plane of the placard, the width of the opening 40 thus presented will be such that the container will snugly fit therein. Obviously the size of the aperture 4 and the wings 12 will be determined by the size of the container 45 with which the placard is to be used.

50 55 From the foregoing description it will be readily understood that when the placard is positioned in association with the container 6, the wings 12 will frictionally engage the side walls of the container and the inner edge 55 of the intermediate portion 18 of the flap 8 will extend transversely of and engage the rear wall of the container. In addition to these foldable members which are adapted to 60 frictionally engage the side and rear walls of 65 the container, I prefer in some instances to

employ a tab or flap member 20 which is adapted to be folded along the line 22, Figure 4. The outer edges of this flap or tab are coincident with the upper edges of the wings 70 12 when said parts occupy the plane of the placard proper, as clearly shown in Figure 4. This tab 20 engages the upper end or top of the container 6, as clearly shown in Figures 2 and 3, and besides providing an additional friction surface, tab or flap 20 provides a fold that greatly increases the rigidity of the display. It will thus be apparent that my improved device is adapted to frictionally engage the top, side and rear walls 75 of the container in such a manner as to securely maintain the placard in proper display position when in use.

80 In Figure 5 I have disclosed an alternative or modified construction in which a depending tab 24 is provided. This tab 24 is not foldable out of the plane of the placard, and hence when the flap 20^a which simulates the flap 20, shown in Figures 1 to 4 inclusive, is bent rearwardly, the tab 24 will project downwardly below the articulation 22^a of the flap 20^a. When a placard provided with the tab 24 is associated with a container, said tab will engage the upper end of the front wall of the container and in this way will provide an additional means to protect against the rearward displacement of the placard. In order to eliminate the unsightly appearance of a tab projecting over the front wall of a container, I propose to apply a portion of the display design upon the tab, as for example 90 in Figure 5 wherein a portion of a roller 95 skate of the disclosed figure is applied to the tab 24.

100 From the foregoing it will be observed that my invention provides a very convenient and inexpensive display device of durable construction which will effectively grip the walls of a container or the like so as to maintain a placard in proper display position. The surface of the wings 12 being of substantial 105 area, renders possible sufficient frictional engagement with the side walls of the container to securely retain the display device in position and the interlocking engagement between the wings and the foldable flap provides a 110 very solid or rigid construction. It is further to be noted that only a relatively small portion of the lower end of the placard proper or panel 3 need be employed for 115 mounting the same upon the container and all of the foldable parts are adapted to lie within the plane of the panel until the same is ready for application to a container. Obviously the particular shape of the wings, as 120 well as the other flaps which have been described, may be varied in order to accommodate particular types of containers, and the sizes thereof may also be varied to suit the 125 particular needs incident to their use. Therefore, it will be understood that my invention 130

is not limited to the particular design of the display device which I have described, but is capable of many other applications and modifications. In this connection it will be understood that the described display device is particularly adaptable for application to containers of rectangular cross section, but it will be equally apparent that my device may be used with containers of different shapes.

5 When my device is used in connection with the types of containers shown in the drawings, it will be seen that the front or exposed surface of the container is entirely exposed, thereby greatly enhancing the value thereof as an advertising medium.

10

It will also be apparent that if the placard were set back sufficiently on the top of the container, and cut continued upward from tab 24 along lines consistent with the pictorial feature (such as the sides of the girl's foot and leg), the foot could be brought forward and rest on the top of the container in front of the placard, forming a brace to prevent the card tipping forward.

15

Having thus described my invention, what I claim as new and desire to secure by Letters Patent is:

1. A device of sheet material of the class described for association with a container or the like including a display panel, a section extending therefrom and adapted when folded out of the plane of the panel to embrace a container, and an element foldable out of the plane of the panel for engagement with the first mentioned section to retain said panel and section in predetermined relative positions.

20

2. A device of sheet material of the class described for application to a container or article of like nature including a display panel, a member thereon adapted when folded out of the plane of the panel to embrace a container, and an element foldable out of the plane of the panel adapted to interlock with the first mentioned member.

25

3. A display device of the class described for use with containers and articles of like nature, including a display panel, a member foldable out of the plane for embracing a container, and an element foldable rearwardly of the panel to lockingly engage the first mentioned member when said member occupies its folded position.

30

4. A display device of the class described for association with a container or like article including a display panel, a member foldable out of the plane of the panel having an intermediate portion adapted to traverse the rear wall of a container, and elements disposed in spaced relation and foldable out of the plane of the panel for locking engagement with the foldable member, said elements being designed to frictionally engage oppositely disposed side walls of the container, whereby

35

the panel is secured in proper display position.

5. A device of sheet material of the class described for application to a container or article of like nature including a display panel, a section extending therefrom and foldable out of the plane thereof which is adapted to embrace the rear wall of the container, and a pair of wing members foldable along a line substantially at right angles to the line of fold of the first mentioned section, said wings being adapted at their free extremities for engagement with the folded section to secure said section in proper folded position and to frictionally engage the walls of the container.

70

6. A device of the class described comprised of sheet material adapted for association with a container or the like including a display panel, a member foldable out of the plane of said panel and adapted to embrace a wall of the container, and elements foldable rearwardly of the panel and adapted to engage and retain the folded member in proper position, said elements being further designed for engaging the walls of the container, whereby the panel is maintained in proper display position without obstructing the forward exposed surface of the container.

80

7. A display device of the class described comprised of sheet material for association with a container or article of like nature, including a display panel, a member foldable out of the plane of the panel having an intermediate portion designed to traverse a wall of a container, and a wing element foldable out of the plane of the panel and provided with a recess at the free extremity thereof which is positioned substantially in a plane which includes the line of fold of the foldable member, said recess being designed to cooperate with said foldable member to secure the same in proper folded position.

95

8. In a display device of the class described for convenient association with containers and articles of like nature, a display panel, a member thereon adapted when folded out of the plane of the panel to embrace a container, an element foldable out of the plane of the panel for engagement with the first mentioned member to retain said panel and member in position, and a second foldable member adapted to engage the top of the container and thereby render the position of the panel more secure.

100

9. A display device adapted for association with a container or article of like nature including a display panel of flat material, a member thereon adapted, when folding out of the plane of the panel, to embrace the container along the rear wall thereof, an element foldable out of the plane of the panel and having a flat surface for engaging a side of the container, and a second element foldable out of the plane of the panel independently of said first foldable element, and adapted to

115

120

125

130

engage the top of the container, said elements being co-operatively arranged to secure the panel in proper display position.

10. In a display device of the class described for attachment to a container or article of like nature, a display panel, a member foldable out of the plane of the panel so as to present a container receiving opening, means foldable out of the plane of the panel for en-

10 gaging the side of the container, and a member depending from the portion of the panel adjacent the container receiving opening, said depending member serving to engage the front wall of the container and thereby secure

15 the same against rearward displacement.

11. In a display device of the class described for attachment to a container or article of like nature, a display panel having a section foldable out of the plane of the panel

20 so as to present a container receiving opening, and an element foldable along a line intersecting the line of fold of the first mentioned section which is adapted to interlock with said section and to frictionally engage a side wall

25 of the container so as to effectively retain the device in proper display position.

12. A display device of the class described comprised of sheet material for association with a container or article of like nature including a display panel, a section thereof being foldable out of the plane of the panel and adapted to traverse a wall of the container, and a pair of wing elements foldable out of the plane of the panel, said wing elements

35 having slots and being adapted to interlock with said first mentioned section whereby said section is secured in a predetermined

position with respect to the display portion

50 of the panel.

40 In witness whereof, I have hereunto subscribed my name.

JOSEPH EDWIN BURGESS.
